UNITED STATES PATENT OFFICE.

JOSEPH B. HOWE, OF WORCESTER, MASSACHUSETTS, ASSIGNOR TO GEORGE S. HARWOOD & SON, OF BOSTON, MASSACHUSETTS, A COPARTNERSHIP CONSISTING OF SYDNEY HARWOOD AND JOHN H. HARWOOD.

SCALE PAN FOR CARD FEEDERS.

Application filed May 15, 1923. Serial No. 639,104.

To all whom it may concern:

Be it known that I, JOSEPH B. HOWE, a citizen of the United States of America, and resident of Worcester, in the county of Worcester and State of Massachusetts, have invented new and useful Improvements in Scale Pans for Card Feeders, of which the following is a specification.

This invention relates to card feeding machines of the kind which embody automatic weighing mechanism, and concerns more particularly a dumping scale pan for use in such weighing mechanism.

Principal objects of the invention are to provide a scale pan of strong and rigid construction and of a cross sectional contour providing for large capacity; to provide a dumping pan whose contents may be discharged substantially instantaneously without setting up appreciable oscillations in the pan or scale beam; and in to provide latch mechanism for determining the retention or discharge of the contents of the pan, such latch mechanism being of simple and dependable construction and releasable with slight effort.

A preferred embodiment of the invention is illustrated in the accompanying drawings, in which:

Fig. 1 is a fragmentary side elevation of a dumping scale pan embodying the present invention showing the same in position to receive a load;

Fig. 2 is an end elevation partly broken away, showing the pan in normal load receiving position;

Fig. 3 is a fragmentary horizontal cross section to larger scale on the line 3-3 of Fig. 2;

Fig. 4 is a detail view illustrating the latch mechanism and associated parts in the position which they assume immediately after the release of the latch; and

Fig. 5 is a detached view showing the latch lever in side elevation.

In accordance with the present invention the pan, which is of generally rectangular contour in cross section, is provided with a pair of rigid end frames of like construction. Each of these frames comprises the substantially parallel spaced side bars 1, 2 united, preferably integrally, at their upper ends by a cross bar 3. Brace members 4, 5 extend obliquely upward and inward from

the lower extremities of the bars 1, 2 respectively and these brace members merge at their upper ends into the enlargement or head 6. The upper portion of this head is preferably united integrally with the top member 3 of the frame as indicated at 7.

This head is furnished with an opening 8 whose upper edge provides the bearing surface 9 which rests upon the fulcrum bar 10. The corresponding surface of the opposite end frame rests upon the fulcrum bar 10^a. The two fulcrum bars are preferably provided with knife edges which are arranged in alignment so that the pan oscillates freely about the axis defined by such knife edges.

Bosses 11, 12 are provided at the upper corners respectively of each end frame, and these bosses are furnished with openings for the reception of the ends of connecting rods 13, 14 which extend from one end frame to the other, and which are secured in the respective bosses by means of set screws 15, 16. The end frames are thus held rigidly in proper spaced relation. Bosses 17, 18 are provided at the lower corners respectively of each end frame, and these bosses are furnished with journal openings for the reception of the ends of rotatable shafts 19, 20 which extend from one end frame to the other.

The side bars 1, 2 of the end frame are furnished with inwardly directed flanges 21, 21^a lying in substantially the same plane, while the brace members 4, 5 are furnished with inwardly directed flanges 22, 23. The plane defined by the latter flanges is spaced slightly from that defined by the flanges 21, 21^a to permit the insertion of a piece of sheet material 24 between the sets of flanges. This sheet material, preferably metal, forms the end wall of the scale pan. This member may be slipped upwardly between the sets of flanges and is secured in position by screws 25. Side wall members 26, 27 are secured by means of screws 28, 29 respectively to the side bars 1, 2 of the end frames. These side walls are preferably formed of sheet material such as sheet steel, and may be made relatively light by reason of the employment of the rigid end frames.

Pairs of brackets 29, 30 respectively are secured to the shafts 19, 20, the brackets of each pair being located adjacent to the ends

of their respective shafts and being secured to the shafts by set screws such as 32. Mov-
able bottom wall members 33, 34 are se-
cured to the respective pairs of brackets.
5 These bottom wall members, which collec-
tively constitute the closure for the bottom
of the pan, are preferably formed of sheet
material and are bent or rolled at their outer
edges to enclose the respective shafts as
10 indicated at 35. The meeting edges of the
respective bottom wall members are pref-
erably rolled or folded to provide strength-
ening beads 36. As shown in Fig. 2 the bot-
tom wall members normally extend down-
15 wardly and inwardly from the axes of their
respective supporting shafts and meet in a
plane below the plane of such shafts. The
end wall members 24 are so shaped as to
20 extend downwardly so as to form complete
closures for the ends of the pan.

A lever 37 is secured to the end of the
shaft 19 by means of a set screw 38. A sec-
ond lever 39 is secured to the end of the
shaft 20 by means of a set screw 39^a. These
25 levers, in the normal position indicated in
the full lines in Fig. 2, extend inwardly
and upwardly, crossing and overlapping at
a point adjacent their free extremities. A
pin 40^a is secured to the end portion of the
30 lever 39. This pin is preferably adjustable
longitudinally of the lever, although such
adjustment is not essential.

The pin 40 projects through an elongate
35 slot 41 formed in the free extremity of the
lever 37. The latter lever is provided with
a boss 42 having a threaded opening for the
reception of a pivot bolt 43 upon which a
latch lever 44 is pivotally mounted.

The tail of this latch lever is provided
40 with a counterweight 45 while its opposite
end is furnished with a lug 46 having an
abutment surface 47. This surface is of
arcuate curvature, described about the piv-
otal axis of the lever as a center, and pref-
45 erably terminates in a shoulder 48. The lever
projects beyond the shoulder 48 to form
an extension 49 for engagement with an ac-
tuating device as will hereinafter be de-
scribed. The lower part of the end frame
50 of the pan is furnished with a bracket 50
from which a lug 51 extends into the plane
of movement of the counterweight 45 of the
latch lever.

The operation of the device is substan-
55 tially as follows, it being assumed that the
pan and its several associated parts nor-
mally occupy the position shown in Fig. 2
while the pan is receiving its load.

In this position the pin 40 is located at
60 the upper end of the slot 41 and is held in
such position by the latch lever whose sur-
face 47 lies immediately behind the pin.
The counterweight 45 normally retains the
latch in this position. When the pin 40 is
65 locked in the upper part of the slot, relative

movement of the levers 37, 39 is prevented,
and when so positioned the bottom wall
members 33, 34 of the pan are closed with
their edges 36 substantially in engagement.

When the pan is to be dumped an actu-
ator, indicated at 52, and which may be of
70 the type disclosed in my copending applica-
tion Serial No. 639,103, filed May 15, 1921,
or which may be of any other desired con-
struction, is caused to engage the extension
75 49 of the latch lever and to swing the latter
about its pivot. Such swinging of the latch
is readily accomplished by reason of the
shape of the abutment surface 47. As soon
80 as the latch has been swung out of engage-
ment with the pin 40, as shown for example
in Fig. 4, the weight of the levers 37, 39 and
associated parts, assisted by the weight of
the contents of the pan, immediately causes
85 the levers to swing downwardly until they
occupy the position indicated in dot and
dash lines in Fig. 2. In the latter position
90 of the levers the movable bottom members
33, 34 of the scale pan stand substantially
vertical as shown in dot and dash lines in
said figure. When in such position, the
bottom walls offer no obstruction whatso-
ever to the delivery of the load from the
pan so that the load is dumped freely and
without any substantial lateral reaction
95 upon the pan such as might set up undesir-
able oscillations therein.

In moving to the dot and dash position
of Fig. 2 the levers 37, 39 swing through the
horizontal plane of their axes and during
such movement the pin 40 first travels to
the left as viewed in Fig. 2, and then as the
levers pass the horizontal position the pin
moves backwardly until it is restored to the
same end of the slot from which it started,
105 as indicated at 40^a, Fig. 2. As the counter-
weight 45 of the latch constantly tends to
restore the latch to operative position, it
would at this time, unless prevented, swing
110 across the slot 41 and prevent restoration
of the levers 37, 39 to normal position. To
prevent this action, the lug 51 is provided
with which the counterweight 45 engages as
the levers drop to their lowermost position.
This prevents upward movement of the lug
115 46 of the latch so that when the restoring
device, indicated at 53 and which may if de-
sired be of the type in my aforementioned
application, is raised into engagement with
the pin 40, the latter is free to move along
120 the slot 41 as the levers 37, 39 are moved
back to normal position. When they reach
the latter position, the lug 46 of the latch
lever immediately snaps beneath the pin 40
thus again locking the parts in the position
125 shown in Fig. 2.

One desirable feature of the pan as above
described arises from its cross sectional
shape which provides a maximum capacity
as respects its outside dimensions without
130

in any way interfering with the discharge of its contents. While the pan here shown is provided with a pair of bottom wall members, it is contemplated that similar locking and latch devices may be employed for controlling closures of other type without substantial modification of the structure disclosed.

I claim:

10. 1. A dumping scale pan comprising a pair of end frames, means for holding said frames each comprising spaced vertical side bars and a horizontal top rail uniting said side bars in fixed relation, side wall members of sheet material fixedly secured to the respective end frames and extending from one to the other, a bottom wall comprising members pivotally mounted to swing about axes adjacent to the lower edges of the respective side wall members, and an end wall member secured to each of the respective frames.

2. A dumping scale pan comprising a rigid end frame having substantially parallel side members, a top member integrally secured to the side members, and a pair of brace members extending diagonally up from the lower ends of the side members and uniting with the top member near its middle point.

3. A dumping scale pan comprising a rigid end frame having substantially parallel side bars and a top bar united therewith, and a pair of brace members extending diagonally upward from the lower ends of the side bars and united adjacent to the upper bar to form a head member having an opening therein for the reception of the pan fulcrum.

4. A dumping scale pan comprising a rigid end frame having members defining two parallel spaced planes, and a piece of sheet material positioned between said members and constituting an end wall for the pan.

5. A dumping scale pan comprising an end frame having substantially parallel side members and diagonally extending brace members, the side members and brace members having flanges respectively which lie in spaced parallel planes, and a sheet metal plate interposed between said sets of spaced flanges.

6. A dumping scale pan comprising a pair of end frames of substantially rectangular contour having openings at each of the corners, a pair of fixed bars secured in the openings at the upper corners of the respective frames and holding the latter in spaced relation, and a pair of shafts journaled at opposite ends in the openings at the lower corners of the respective frames.

7. A dumping scale pan comprising a fixed side wall, a shaft journaled adjacent to the lower edge of said wall, a bracket se-

cured to the shaft adjacent to each of its ends, and a sheet metal bottom member secured to the brackets, one edge of the bottom member being bent to enclose the shaft and its opposite edge being rolled to provide a strengthening bead.

8. A dumping scale pan comprising a pair of bottom members hinged to swing about substantially parallel axes, an arm secured to each of said members, said arms normally overlapping, an abutment carried by one arm, and a latch mounted upon the other arm and engageable with the abutment normally to hold the bottom members in closed position.

9. A scale pan having a movable closure, and means normally preventing movement of said closure comprising an abutment member, a latch normally engaging said abutment member to prevent movement thereof, said latch being movable to release said abutment, and means operative to prevent reengagement of the latch with the abutment prior to the restoration of the latter to initial position.

10. A dumping scale pan comprising a pair of hinged bottom members, oppositely directed arms secured to the respective members, one of said arms having an elongate slot and the other having a pin projecting into said slot, and latch means normally operative to prevent movement of the pin longitudinally of the slot.

11. A scale pan having a movable bottom member and means normally holding said bottom member in closed position comprising a relatively movable member, a pin projecting from one member into an elongate slot in the other, a latch device normally positioned to hold the pin at one end of said slot, said latch being movable to release the pin and allow it to move along the slot, and means to prevent reengagement of the latch with the pin before the parts are restored substantially to initial position.

12. A dumping scale pan comprising a pair of hinged bottom members, an arm fixedly secured to each of said members to swing therewith, said arms extending diagonally toward each other and overlapping at their free extremities, a pin projecting from one of said arms through an elongate slot in the other, and a latch carried by the slotted arm and normally preventing movement of the pin longitudinally of the slot.

13. A dumping scale pan comprising a pair of relatively fixed side walls, a bottom member hinged to the lower edge of each side wall, an arm secured to each bottom member to turn therewith, said arm normally extending inwardly and upwardly and overlapping at their extremities, a pin projecting from one arm through an elongate slot in the other, and a latch lever pivotally supported upon the latter arm.

said latch lever having an element normally engaging the pin to prevent movement thereof along the slot.

14. A scale pan having a movable bottom member and means normally holding said member in closed position comprising a pair of levers normally extending diagonally upwardly toward each other from their pivotal axes, a pin projecting from one into an elongate slot in the other, a latch normally holding said pin in the upper end of the slot, said latch being releasable to permit the pin to move in the slot thereby allowing the levers to turn until the pin passes the plane of the levers and returns to the same end of the slot, and means to prevent engagement of the latch with the pin while the parts occupy the last named position.

15. A dumping scale pan comprising a movable closure and a pair of swinging lever arms for controlling the movement of said closure, said arms normally intersecting at an angle to each other, a pin projecting from one of said arms and engaging a guide element on the other arm, a latch lever pivoted upon the latter arm having a contact element normally engaging the pin to prevent movement of the latter relatively to the guide element, and a counterweight on the latch lever tending to hold the latter in operative position.

16. A latch device for use in a dumping scale pan having a movable closure comprising a lever pivoted at its central portion and having a latch lug near one end, a projection extending beyond the lug for engagement by an actuating element, and a counterweight at its other end.

17. A dumping scale pan comprising movable bottom members and a pair of swinging arms for controlling the movement thereof, said arms crossing and overlapping each other at their free extremities, a pin projecting from one of the arms through an elongate slot in the other, and a latch lever pivoted to the slotted arm, said latch lever having an arcuate contact surface concentric with the axis of the latch lever normally engaging the pin to prevent movement of the latter.

18. A scale pan having bottom members hinged at its opposite edges, a lever secured to each member adjacent to its axis, said levers normally extending inwardly and upwardly, a pin projecting from one member through an elongate slot in the other, a latch lever pivoted to the slotted member and having a stop lug normally engaging the pin to hold the latter adjacent to the outer extremity of its slot, and a member adapted to be engaged by an actuating element for swinging the latch to release the pin.

19. Latch mechanism for a dumping scale pan comprising a pair of angularly disposed levers normally crossing adjacent to their free extremities, a pin projecting from one lever into an elongate slot in the other, a latch lever pivotally mounted upon one lever and having a part normally engaging the pin thereby locking the levers against pivotal movement, said latch lever being movable to release the pin thereby permitting it to move along the slot and as the levers continue to swing to move back again to its initial position, and a lug engageable by the tail of the latch lever to hold the latter out of engagement with the pin when the latter occupies the last named position.

20. A scale pan comprising a movable closure and means for controlling its movements comprising a pair of levers pivoted to swing about horizontal axes lying in the same plane, said levers normally crossing at a point above said plane, a pin projecting from one lever into a slot in the other, a latch lever normally holding the pin at one end of the slot whereby to lock the levers against movement said latch being movable to release the pin thereby allowing it to move toward the other end of the slot as the levers swing through the plane of their axes and to resume its position at the first end of the slot as the levers swing below said plane, and a device engageable with the latch as the levers approach the last named position to prevent reengagement of the latter with the pin.

Signed by me at Boston, Mass., this 3d day of May 1923.

JOSEPH B. HOWE.
